MATERIAL HANDLING APPARATUS

Abraham Kleiman, 76 Spruce Lane, Valley Stream, N.Y.

Filed Oct. 9, 1959, Ser. No. 845,561

1 Claim. (Cl. 214—1)

This invention relates to material handling apparatus and, more particularly, to a device for handling a mattress.

Ordinarily, it is difficult for one person to lift and turn a mattress as is often required when changing bed linens, and the like. It is therefore an object of the present invention to provide material handling apparatus particularly suited for handling large and bulky items, such as mattresses, that is extremely simple in construction, efficient in operation, and which will allow a single person to perform such tasks in a simple and efficient manner.

Another object of the present invention is to provide a mattress handling unit that can be conveniently collapsed and stored when not in use, may be readily erected and used by a single person, and which has mechanical advantage means for lifting and turning such heavy items as bed mattresses.

Still another object of the present invention is to provide material handling apparatus of the type described that is completely self contained, stable, readily erected and collapsed, and which can be stored in a relatively small area when not in use.

All of the foregoing and still further objects and advantages of this invention will become apparent from a study of the following specification, taken in connection with the accompanying drawing, wherein:

FIGURE 1 is a perspective view, with parts broken away, of material handling apparatus made in accordance with the present invention in actual use;

FIGURE 2 is an enlarged fragmentary side elevational view, partly in section, of certain parts of the apparatus shown in FIGURE 1;

FIGURE 3 is an enlarged fragmentary cross sectional view of a manually operated winding device forming a part of the present invention;

FIGURE 4 is a fragmentary side elevational view of certain parts of the winding mechanism shown in FIGURE 3;

FIGURE 5 is a fragmentary side elevational view, with parts broken away, of an upper extension portion of the apparatus shown in FIGURE 1;

FIGURE 6 is a perspective view of an adapter assembly for handling certain types of mattresses with the apparatus shown in FIGURE 1; and

FIGURE 7 is an enlarged fragmentary plan view of certain parts of the adapter shown in FIGURE 6.

Referring now to the drawing, and more particularly to FIGURE 1 thereof, material handling apparatus 10 made in accordance with the present invention is shown to include a main frame having a pair of spaced apart parallel sides 12 integrally connected together at one upper end by means of a transversely extending bight portion 14. Foot pads 16 are attached to the opposite lower ends of the sides 12 to prevent slippage, damage to the supporting surface, and quiet operation of the assembly.

The lowermost end of each side 12 is also provided with a bracket 18 upon which a pivot pin 22 hingedly connects one end of a pair of legs 20 that are selectively rotatable between a normally laterally outwardly extended position and an upwardly folded parallel position with respect to the main frame. The outermost free end of each such leg 20 is also provided with a cushion pad 24 which functions in a manner similar to that of the pads 16 of the sides 12 of the main frame. A cross rod 26 maintains the legs 20 in spaced apart parallel relation-

2

ship, and further serves as a bearing for one end of a collapsible brace arm 28 that is connected at its opposite end by means of a pivot pin 32 to an inverted channel stop member 30. Another pivot pin 34 pivotally connects one end of another brace arm 36 to the stop member 30, while the opposite free end of the other such brace arm 36 is pivotally connected by means of a pivot pin 38 to an outwardly extending lug 40 of a cross piece 42 integral with sides of the frame intermediate the opposite ends thereof. It will thus be recognized that the stop member 30 is movable to an off center position when the legs 20 are opened, thus providing a stable collapsible base for the main frame which is locked in the open position until the ends of the brace arms 28, 36 adjacent to the stop member 30 are rotated outwardly in a direction away from the brackets 18 to permit the legs 20 to be folded into the collapsed parallel position with respect to the main frame, such as shown in broken lines in FIGURE 2. In such folded collapsed position, the entire unit may be conveniently stored in a small area.

A post 44 is secured to the central portions of the cross piece 42 and bight portion 14 of the main frame and has an upwardly opening longitudinal bore 46 that slidably receives a depending stud 48 of an upper extension member 50 having a similar longitudinal bore 52. A pair of aligned openings 53 in diametrically opposite sides of the extension member 50 rotatably support a cross shaft 54 having a cable winding sheave 62 centrally mounted thereupon. A non-circular counter bore 56 adjacent to one of the aligned openings 53 slidably and releasably receives a similarly shaped stop plate 58 secured to the cross shaft 54 adjacent to a perpendicularly related crank handle 60. Thus, the sheave 62 and supporting shaft 54 may be locked in any desired rotated position simply by pushing the shaft 54 inwardly of the extension member 50 to engage the stop plate 58 within the counter bore 56.

A flexible cable 64 has one end secured to the winding sheave 62, the opposite end of which is trained over a guide pulley 66 mounted upon a rotatable shaft 68 that is carried by a pair of longitudinally extending ears 72 at the uppermost end of an angularly related terminal portion 73 of the vertical post 50 which overlies the base formed by the laterally extending legs 20 in the open position. The cable 64 is guided outwardly from the longitudinal bore 52 of the supporting extension member 50 through a slot 70 formed between the ears 72 of the angular extension member 73. The outermost extremity of the flexible cable 64 is provided with a hook 65 that is intended to engage a central portion of a flexible bridle member 74 having hooks 76 at the opposite ends thereof which may be used to releasably engage the hand holds 78 on the side of a mattress 80.

The operation of the apparatus will now be readily understood. By opening the legs 20, and securing them in the open position by moving the stop member 30 of the brace arms 28, 36 to the off center position shown in FIGURE 2, the depending stud 48 of the vertical extension 50 may be inserted into the bore 46 of the mounting post 44 so that the angular extension portion 73 overlies the base, thus providing maximum stability. Thus, by attaching the hook 65 of the flexible cable 64 of the bridle 74 that has been attached to the handholds 78 of the mattress, actuation of the crank handle 60 will elevate the adjacent side of the mattress 80 to bring the opposite side of the mattress over to the side of the bed adjacent to the main frame of the apparatus. Once the mattress has been so elevated, it is then only necessary to rotate the elevated side of the mattress outwardly toward the opposite side of the bed, to complete the mattress turning procedure.

With reference now to FIGURES 6 and 7 of the drawing, an adapter unit 85 is shown which may be conveniently used with any mattress that does not have hand holes 78 along the sides thereof. This adapter 85 includes a substantially rigid support plate 86 having transversely extending slots 87 at the opposite ends thereof. A flexible strap 88, such as a webbed strap are received within the transversely extending slots 87 and turned backwardly into overlying engagement with an adjacent portion of the strap to define a loop, such loop being closed in any suitable manner, such as by a rivet 89 to secure the strap and plate together. The plate 86 is also provided with hook receiving openings 90 for releasably receiving the hooks 76 at the opposite ends of the bridle member 74, thus providing a convenient means for attaching the bridle and permitting use of the hook 65 of the flexible cable 64. If desired, one end of the strap 88 may be provided with a buckle or tightening device so as to facilitate insertion and securing of the side of the mattress 80 within the adapter 85.

It will be recognized that any desired type of ratchet, spring, or clutch mechanism may be included in the winding sheave 62, without departing from the teachings of the present invention. For example, a spring may be used to yieldably maintain the winding sheave in the locked position to prevent accidental unwinding thereof when handling the mattress in the elevated position. Also, the knob of the handle may be pivotally mounted thereupon so as to prevent it from becoming jarred accidentally while the mattress is in an elevated position. The apparatus may also include a built in clutch which will permit the cable to unwind rapidly when actuated, to thus facilitate the lowering of the mattress to the desired position without having to manually unwind the sheave throughout the entire distance.

Because of the mechanical advantage arrangement and the stable base and upright supporting parts, it is a relatively simple matter for a single person to elevate and manipulate heavy objects, such as bed mattresses, in a simple and efficient manner without strain, exertion, or the like. It is therefore possible to employ this col-

lapsible material handling apparatus for other household purposes wherever it is necessary to elevate heavy loads or objects for any purpose whatsoever.

While this invention has been described with particular reference to the construction shown in the drawing, it is to be understood that such is not to be construed as imparting limitations upon the invention, which is best defined by the claims appended hereto.

Having thus described my invention, I claim as new and desire to secure by Letters Patent:

5 Material handling apparatus comprising, in combination, a self supporting frame, a base foldably carried by one lower end of said frame for movement between a laterally outwardly extending open position and a side by side parallel folded position, a flexible cable, cable winding means carried by said frame, said cable having one end connected to said winding means, and guide means at the opposite upper end of said frame directing said flexible cable from said winding means, said frame being 10 substantially inverted U-shaped having a pair of spaced 15 apart parallel legs connected together at one upper end by a transversely extending bight portion, and a vertical mounting post carried by said inverted U-shaped frame intermediate said spaced apart parallel sides thereof, said 20 base comprising a pair of spaced apart parallel legs each pivotally carried upon the lowermost end of one of said sides of said frame, and collapsible brace means 25 releasably securing said legs in an open laterally outwardly extended position with respect to said frame.
